UNITED STATES PATENT OFFICE.

CHARLES H. NORTON, OF PROVIDENCE, RHODE ISLAND, ASSIGNOR TO THE BROWN & SHARPE MANUFACTURING COMPANY, OF SAME PLACE.

GRINDING-MACHINE.

SPECIFICATION forming part of Letters Patent No. 626,337, dated June 6, 1899.

Application filed April 25, 1898. Serial No. 678,757. (No model.)

To all whom it may concern:

Be it known that I, CHARLES H. NORTON, of the city and county of Providence and State of Rhode Island, have invented certain new and useful Improvements in Grinding-Machines; and I do hereby declare the following specification, taken in connection with the accompanying drawings, forming a part of the same, to be a full, clear, and exact description thereof.

In grinding-machines where straight and tapered work is to be ground to minute accuracy it is desirable that the table upon which the head and foot stocks are guided and held be so constructed that the centers will always lie in the same straight line at whatever point on said table they may be located. In practice I have found that with the usual horizontal surface for guiding the head and foot stocks the area of the guiding-surface or straight-edge for maintaining the centers in the same straight line at whatever point along the table they are situated is necessarily small, with the result that said guiding-surface soon becomes worn, causing errors in the alinement of the centers and consequent inaccuracies in the work. The wear and errors are increased in cases where the stocks are drawn against the guiding edge, and in these cases errors may also be caused by drawing the stocks against the straight-edge with varying force, owing to the yielding of oil, moisture, or dirt between the straight-edge and the stock. Moreover, water, ground particles of steel, emery, or dust are liable to get between the horizontal guiding-surface and the stocks and raise or tip said stocks from their true position, making it impossible to fasten them at different points along the table with sufficient accuracy. One object of the present invention is to overcome these objections and to provide a guide for the head and foot stocks which shall have a large area for maintaining the centers in alinement horizontally—that is, in the direction in which an error would produce the greatest inaccuracy in the work.

A further object is to provide a means for clamping the head-stock and foot-stock which will allow the clamping pressure to vary with-

out materially affecting the accurate alinement of the centers.

A further objection to the grinding-machines as heretofore constructed is that the guide for the head and foot stocks is so constructed and arranged that water and dirt from the grinding will get upon said surfaces unless said guide is protected by so-called "water-guards," which are formed in sections and must be inserted between the head and foot stocks after they have been adjusted to the proper position. These water-guards are usually telescoped or lapped one upon the other to a certain extent; but in all cases they must be removed and replaced in position in changing the adjustment of the centers for different lengths of work. Moreover, these guards are not perfectly water-tight, and a small amount of water and dirt works through upon the grinding-surfaces and is liable to destroy the accuracy of the centers when they are adjusted for a different length of work.

A further object of the invention is accordingly to provide a table so constructed that the guiding-surfaces are fully protected from water and dirt without the use of guards, which must be removed and replaced for different lengths of work.

A further object of the invention is to provide means for obtaining accurate adjustment of the slide upon which the grinding-wheel is mounted. In machines for accurate grinding this slide must be moved in ordinary use as little as one-eighth of one-thousandth of an inch and many times as little as one-twentieth of one-thousandth of an inch, and these small adjustments, as well as the larger adjustments, must be made accurately and be maintained, as any error in adjustment of the slide produces double such error in the work. The slide must also be heavy to prevent vibration of the revolving wheel, and to move this heavy weight the small amounts necessary for accuracy of work requires that all conditions of friction and oil be the best and that there be no torsion in the connections between the indexing-wheel and the slide on which the grinding-wheel is mounted. Even in cases where by reason of favorable conditions and great care the required accurate

adjustment of the wheel-slide is obtained the jarring of the floor or machine will often cause the slide to advance from one-twentieth to one-quarter of a thousandth of an inch, causing the wheel to cut the work too small. In fact it is very seldom that an operator will succeed in moving the wheel-slide accurately to these delicate measurements, but must usually move it less than desired to insure against cutting the work too small and then by very skilful jarring of the index-wheel obtain as near as possible the desired adjustment. Again, when it is desired to move the wheel a definite amount by the aid of the index-wheel with its graduations it is nearly impossible to find the exact point where all backlash is taken up and the slide really begins to move.

I have found by experiment that even when all connections between the grinding-wheel slide and index-wheel are the best yet the oil on the revolving and thrust bearings of these connections will yield and store up energy enough to cause a horizontal slide to move uncertain amounts even though the sliding contact be very loose and the slide is floating freely on the best oil. In such a case also jars usually cause those slight movements of the slide toward the work which result in the errors above referred to.

As far as I know, previous to my invention all grinding-machines were subject to the errors and objections referred to, which it is one of the objects of my invention to overcome. This I have accomplished by placing the grinding-wheel slide upon an incline sufficient to cause it to slide down the incline by gravity even when the conditions of friction and oil are not the best. With this construction a part of the weight of the slide is transferred from the sliding surface to the bearings of the moving connections, where it is more easily carried, and the friction upon the sliding surface is reduced. Moreover, with this construction the slide rests firmly upon its moving mechanism, and it is possible to allow the sliding contact between the slide and its support to be very loose and to float the slide freely upon oil, and a jar can cause no movement of the slide toward the work. The torsion of the connections, moreover, remains practically wound up or constant, so that any perceptible movement of the index-wheel either way is followed by a corresponding movement of the slide. I find with this construction I am enabled to grind duplicate work within narrow limits of accuracy without any skill or caution except to place the index-wheel at the proper graduation, thus making it possible for accurate work to be done by relatively-unskilled labor and also making it possible to use automatic graduating or feeding devices for the slide.

A further object of the invention is to provide means for carrying a bearing-block which may be readily swung into or out of operative position and which does not inter-

fere with the swing of the work or the use of a water-guard to protect the ways on which the head and foot stocks are mounted. This is accomplished by providing an arm, which is mounted in a bearing at the rear of the work-centers and in a fixed relation to the support for the wheel-slide, which arm extends over and downward, overhanging the work, and carries the bearing-block at its front end. With this construction the front end of the arm may be swung up out of the way when not in use or when the work is to be changed and is always in position where it can be readily and quickly swung into position to bring the bearing-block against the work in front of the grinding-wheel. Moreover, by thus mounting the bearing-block the use of a water-guard is not interfered with nor is the swing of the machine reduced, as would be the case with an arm extending below the work.

Referring to the drawings, Figure 1 is a front elevation showing a grinding-machine embodying the various features of invention in their preferred form, and Fig. 2 is a transverse sectional view. Fig. 3 is a sectional view showing the overhanging arm and its supporting-bracket. Fig. 4 is a front elevation of the same, and Fig. 5 is a sectional detail showing the means for clamping the stocks in position.

The frame 1 of the machine is provided with ways 2, on which is guided the longitudinally movable bed 3. The bed may be operated to carry the work across the face of the grinding-wheel 4 by any suitable and well-known mechanism. The table for supporting and carrying the head and foot stocks is mounted on the bed 3 and is preferably connected therewith by a pivot 6, so that said table may be adjusted for either straight or taper work in a well-known manner. The table is substantially triangular in cross-section and is provided with a base 7, which rests upon the upper surface of the bed 3, an upwardly-extending front side 8, and a rear side 9, upon which is formed a longitudinally-extending way 10. The face 11 of this way is substantially vertical, and said way is provided with an upper beveled edge 13 and a lower beveled edge 14. The head-stock 15 and the foot-stock 16 are mounted upon the way 10 and are provided with shoulders 17, which engage the upper beveled edge 13, and bearing-faces 18, which engage the face 11 of said way. The head and foot stocks are also provided with clamping-jaws 19, which are drawn against the lower beveled edge 14 by bolts 20 and nuts 21 and serve to secure the stocks in position on the way.

The head and tail stocks extend forward over the upper edge of the table and preferably downward below said upper edge, so that the work is supported out of line with the way 10, and any water or grit dropping down from the work will not strike the said way, but will run down the side 8 of the table and fall into

the trough 22. In order to prevent any water or grit thrown off by the work or grinding-wheel from falling on the way 10, the front side 8 of the table is preferably extended over 5 and beyond the rear side, so that the upper edge overhangs the rear side and effectively shields the way 10. By thus forming the table so that it is substantially triangular in cross-section not only is a permanent water-guard 10 provided for the way on which the head and tail stocks are mounted, but the shape of the table is such that it will resist strains by which the tables ordinarily used would be deflected from a straight line.

15 By mounting the head and tail stocks upon a substantially vertical way it will be seen that a broad bearing-surface is provided for maintaining the alinement of the centers in the direction in which an error will produce 20 the greatest inaccuracy in the work. Thus it will be apparent that any movement of a center out of line horizontally will result in double the error in the work, while any slight movement out of line vertically will not materially affect the accuracy of the grinding. With the vertical way having a broad bearing-face alinement horizontally is more accurately maintained than heretofore.

25 By providing the way with beveled edges and using a clamp for engaging one of said edges the pressure of the clamp on the beveled edge may vary without materially affecting the pressure between the broad faces of the stock and way and the danger of error due to unequal pressure upon the oil between 30 said surfaces is prevented.

35 The form of table shown combines all the advantages above set forth; but it will be understood that tables may be designed which will 40 embody some of said advantages without embodying all and that such tables would be within my invention, the various features of which are not limited in their scope to constructions in which all said features are 45 present.

45 The grinding-wheel 4 is mounted in the slide 23 in any well-known manner. The slide is mounted on an inclined way 24, carried by the frame 1, the inclination of the way being 50 such that the slide will move down the way by gravity. A rack 25 is secured to the under side of the slide and is engaged by a gear 26, which meshes with a gear 27, secured to a short shaft 28. A worm-wheel 29 is also secured to shaft 28 and is engaged by a worm 55 30, secured to a transverse shaft 31, provided with a hand-wheel 32 at the front of the machine. An index-wheel 33 is secured to the shaft 31 and turns under a pointer 34, secured 60 to the frame. The functions effected by mounting the grinding-wheel slide upon an inclined way have already been fully set forth and need not be here repeated.

65 It will be understood that any suitable means may be employed for operating the grinding-wheel slide and that the invention is not limited to the mechanism shown for

that purpose. In order that the machine may be adapted for taper-work, it is necessary that the axis of the grinding-wheel and the 70 axis of the work should remain in the same plane whether they are parallel or at an angle to each other and whatever the position of the grinding-wheel slide upon its way. Means are therefore provided for maintaining 75 the work-supporting centers and the axis of the grinding-wheel in the same plane. In the construction shown this is accomplished by providing the bed on which the work-supporting table rests with an inclined upper surface 80 parallel to the way on which the grinding-slide is supported.

An arm 35 is mounted in a bearing 36, formed in a bracket 40, which is secured to the support on which the grinding-wheel slide is 85 mounted and bears a fixed relation to the ways on which said slide is mounted. The front end of the arm when in operative position extends over and downward in front of the work-centers and is provided with guides 41 for supporting and guiding a bearing-block 37, which may be adjusted in said guides by a screw 42. The overhanging arm may be clamped in its bearing by any means, as by the binding-bolt 43. When the bearing-block is in use, the 90 arm is swung down into the position shown in Figs. 3 and 4, with the bearing-block in position in front of the grinding-wheel, and said block is adjusted by the screw 42 to engage and steady the work 44. When the bearing-block is not in use or when the work is to 95 be changed, the arm may be swung up out of the way, but where it may be quickly and conveniently thrown into operative position.

A tool-socket 38 is preferably formed on the 100 foot-stock, in which socket a truing-tool may be held by a set-screw 39 and the grinding-wheel sharpened or trued without removing the work from the centers.

105 While the invention has been shown and described in connection with a machine in which the work is fed across the face of the grinding-wheel and in which the work-centers are adjusted for taper-work, it will be understood that the invention may be applied 110 to those machines in which the grinding-wheel travels longitudinally or to those in which the grinding-wheel travels and in which the longitudinal ways for guiding the grinding-wheel 115 support are adjusted for taper-work.

120 What I claim as my invention, and desire to secure by Letters Patent, is—

1. In a grinding-machine, the combination with the grinding-wheel support, of a support for the head and foot stocks having an upwardly-extending front side, a way upon the rear side of said support, and head and foot stocks mounted on said way and extending forward over the upper edge of the support, and carrying centers located vertically above 125 the front side, substantially as described.

2. In a grinding-machine, the combination with the grinding-wheel support, of a support for the head and foot stocks having an up-

wardly-extending front side provided with an overhanging upper edge, a way upon the rear side of the support under said overhanging edge, and head and foot stocks mounted on 5 said way and extending forward over said edge, substantially as described.

3. In a grinding-machine, the combination with the grinding-wheel support, of a table having an upwardly-extending front side, a 10 way upon the rear side of said table, and head and foot stocks mounted on said way and extending over and below the upper edge of said table, substantially as described.

4. In a grinding-machine, the combination 15 with the grinding-wheel support, of a table having an upwardly-extending front side, a substantially vertical way upon the rear side of said table having upper and lower beveled edges, and head and foot stocks mounted upon 20 said way, substantially as described.

5. In a grinding-machine, the combination with the grinding-wheel support, of a table having an upwardly-extending front side, provided with an overhanging upper edge, a way 25 upon the rear side of the table undersaid overhanging edge, and head and foot stocks mounted on said way and extending over and below said upper edge, substantially as described.

6. In a grinding-machine, the combination 30 with the grinding-wheel support, of a table substantially triangular in cross-section, a substantially vertical longitudinal way on the rear side of said table, and head and foot stocks mounted on said way, substantially 35 as described.

7. In a grinding-machine, the combination with the grinding-wheel support, of a table substantially triangular in cross-section, and having the front side extending over and 40 above the rear side, a longitudinal way upon the rear side of said table, and head and foot stocks mounted on said way, substantially as described.

8. In a grinding-machine, the combination 45 with the grinding-wheel support, of a table substantially triangular in cross-section, a longitudinal way upon the rear side of said table, and head and foot stocks mounted upon 50 said way and extending forward over the upper edge of the table and carrying centers located vertically over the front side, substantially as described.

9. In a grinding-machine, the combination with the grinding-wheel support, of a table 55 substantially triangular in cross-section and having the front side extending over and above the rear side, a longitudinal way upon the rear side of said table, and head and foot stocks mounted upon said way and extending 60 forward over the upper edge of the table, substantially as described.

10. In a grinding-machine, the combination with the grinding-wheel support, of a table 65 substantially triangular in cross-section and having the front side extending over and above the rear side, a longitudinal way upon

the rear side, head and foot stocks mounted upon said way, and extending over and below the upper edge of the table, substantially as described.

11. In a grinding-machine, the combination with the grinding-wheel support, of a table, a substantially vertical way extending longitudinally of said table, and head and foot stocks mounted upon said way, substantially 75 as described.

12. In a grinding-machine, the combination with the grinding-wheel support, of a table, a substantially vertical way extending longitudinally of said table and having upper and 80 lower beveled edges, head and foot stocks mounted upon said way, and clamps upon said head and foot stocks for engaging the lower beveled edge, substantially as described.

13. In a grinding-machine, the combination 85 with the head and foot stocks for the work-centers, of a grinding-wheel slide, an inclined way upon which said slide is mounted, means for moving said slide on said way, and means for maintaining the work-centers and the axis 90 of the grinding-wheel in a plane parallel to said way, substantially as described.

14. In a grinding-machine, the combination of a grinding-wheel slide, an inclined way upon which said slide is mounted means for 95 moving said slide on said way, a bed having an upper surface parallel to said way, a table pivoted upon said surface and head and foot stocks mounted on said table, substantially as described.

15. In a grinding-machine, the combination 100 of a grinding-wheel slide mounted on an inclined way, means for moving said slide on said way, a bed having an upper surface parallel to said way, a table substantially triangular 105 in cross-section pivoted on said upper surface, a way on the rear side of said table, and head and foot stocks mounted on said way and extending forward over the upper edge of said table, substantially as described. 110

16. In a grinding-machine, the combination with a table, head and foot stocks supported on said table, a grinding-wheel slide, an overhanging arm mounted in the rear of work-centers and having its front end located in front 115 of said centers and a bearing-block carried by said arm, substantially as described.

17. In a grinding-machine the combination with a table, head and foot stocks supported on said table, a grinding-wheel slide, a bearing in the rear of the head and foot stocks and in fixed relation to the support for the grinding-wheel slide, an arm mounted in said bearing and having its front end extending over and downward and provided with means 125 for supporting a bearing-block, substantially as described.
